CONTROL FOR A GAS VACUUM AUTOCLAVE

Alfred B. Huston, Wyckoff, N.J., assignor to Vernitron Corporation, Great Neck, N.Y.

Filed Feb. 6, 1970, Ser. No. 21,301

Term of patent 14 years

Int. Cl. D24—02

U.S. Cl. D83—1

FIG. 2

FIG. 1

FIG. 5

FIG. 3

FIG. 6

FIG. 4

FIG. 7

FIG. 1 is a perspective view of a control for a gas vacuum autoclave showing my new design;

FIG. 2 is a front elevational view thereof;

FIG. 3 is a bottom plan view thereof;

FIG. 4 is a top plan view thereof;

FIG. 5 is a left-side elevational view thereof;

FIG. 6 is a right-side elevational view thereof;

FIG. 7 is a rear elevational view thereof.

I claim:

The ornamental design for a control for a gas vacuum autoclave, substantially as shown.
